DESIGN FOR AN ADVERTISING DISPLAY UNIT OR SIMILAR ARTICLE

Charles J. Strauss, Wheeling, W. Va., assignor to Advertising Corporation of West Virginia,
Wheeling, W. Va., a corporation of West
Virginia

Application January 30, 1940, Serial No. 89,881

Term of patent 7 years

To all whom it may concern:

Be it known that I, Charles J. Strauss, a citizen of the United States of America and resident of Wheeling, county of Ohio and State of West Virginia, have invented a new, original, and ornamental Design for an Advertising Display Unit or Similar Article, of which the following is a specification, reference being had to the accompanying drawing, forming part thereof, in which—

I claim—

The ornamental design for an advertising display unit or similar article, substantially as shown.

CHARLES J. STRAUSS.
